UNITED STATES PATENT OFFICE.

WILLIAM H. WILLIAMS, OF KEY WEST, FLORIDA.

JACK-SCREW.

SPECIFICATION forming part of Letters Patent No. 235,481, dated December 14, 1880.

Application filed October 1, 1880. (No model.)

To all whom it may concern:

Be it known that I, WILLIAM H. WILLIAMS, of Key West, in the county of Monroe and State of Florida, have invented a new and Improved Jack-Screw, of which the following is a specification.

This invention relates to that class of devices that are designed for lifting heavy bodies.

The invention consists in a peculiarly-constructed pawl, made detachable and combined with a bifurcated lever provided with side bolts, as hereinafter described.

Figure 1 is a partly-sectional vertical elevation of the device. Fig. 2 is a longitudinal elevation of the pawl. Fig. 3 is a cross-section of the ratchet, showing its attachment to the screw.

Similar letters of reference indicate corresponding parts.

In the drawings, A represents the base-block of the device, provided on its under side with pointed studs *a a*, to hold it in place, and provided, also, with a hemispherical recess, *b*, for convenience of fitting the washer and pin *c d* respectively on the lower end of the screw B, whereby the said screw B is held in an upright position.

B is a square threaded screw, provided with a square shank, as shown at *f*, below the screw-threads, on which shank *f* is fitted the ratchet C; and immediately below the square portion *f* the screw-shank is round for a short space, as shown at *g*, and then turned down to form a spindle, *h*, that is inserted through the center of the base A, and has the washer *c* secured upon it by the pin *d*, as aforesaid. The shoulder *i*, formed by turning down the spindle *h*, rests on the top of the base A, and also serves to support the screw B in an upright position.

D is a bifurcated rotatable lever-socket, provided with collars *k k*, encircling the screw B above and below the ratchet C, and provided

with a detachable pawl, F, that is hooked on a vertical bolt, *m*, and held against the ratchet C by a spring, E, which is secured on the handle D' of the lever-socket D by a thumb-screw, E'. This pawl F is provided with an inner concave surface, as shown at *q*, so that the teeth of the ratchet C, working against said pawl F, will easily release it, so that the spring 45 E may press it into the interspaces between said ratchet-teeth; and said pawl F is also provided with a curved slot, *r*, by means of which it is engaged or hooked on the bolt *m*. Both sides of the lever D are provided with bolts *m*, 50 so that, a reverse action of the jack-screw being required, the pawl F can be unhooked from one bolt *m* and hooked upon the other bolt *m*, and the said pawl F can at any time 55 be removed altogether from the device to insure that the said jack-screw, when in operation, shall not be tampered with by unauthorized persons.

G is a long cylindrical screw nut or cap, having a solid flat flanged head, the face of 65 which is provided with pointed studs *o o*, for the better holding of said cap G against all objects resting on it. Interiorly said cap G is screw-threaded, as shown at *p*, in its lower portion, that it may move by the turning of 70 the screw B. The interior of the upper portion of the cap G is made with a smooth bore, as shown at *s*.

Having thus fully described my invention, I claim as new and desire to secure by Letters 75 Patent—

In a jack-screw, the combination, with the bifurcated lever D, provided with bolts *m*, of the detachable slotted pawl F, substantially as and for the purpose described.

WILLIAM HENRY WILLIAMS.
